UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

REINFORCEMENT FOR THIN METAL SHEETS AT RIVETED CONNECTIONS.

1,178,492.

Specification of Letters Patent.

Patented Apr. 11, 1916.

Application filed February 18, 1914. Serial No. 319,482.

To all whom it may concern:

Be it known that I, CLAUS J. WERNER CLASEN, a citizen of the United States of America, and resident of Davenport, Scott county, Iowa, have invented a certain new and useful Improvement in Reinforcement for Thin Metal Sheets at Riveted Connections, of which the following is a specification.

10 My invention relates to improvements in reinforcement for thin metal plates at points where connections are to be riveted thereto and has for its object the increasing of the sectional area of the plate at the point of intersection by the rivet without projecting anything but the rivet head beyond the surface of the plate.

I have chosen to illustrate my improved reinforcement as applied to the securing 20 of ladder rounds or grab irons to the sides or ends of an ordinary freight car, which sides or ends consist of thin steel plates instead of the usual wood construction. I accomplish this in the manner shown in the 25 accompanying drawing, in which—

Figure I is an elevation of a portion of a car side showing my improvement as applied to several ladder rounds. Fig. II is an enlarged plan view of the ladder round 30 connection. Fig. III is a cross section thereof.

The grab irons or ladder rounds of an ordinary freight car are usually located on the side of the car near the end thereof.

35 One end of the round, in the case of a car provided with an all steel superstructure, is usually riveted solidly to the heavy steel corner post which is invariably of a thickness to insure a substantial and safe fastening.

40 The other end of the rounds, however, must necessarily be secured directly to the body of the car and when this body consists of a thin steel plate or sheet, the fastening of a round thereto by simply

45 punching a rivet hole in so thin a sheet and

securing the round by riveting is too insecure and so temporary in its serviceability as to fail to meet the requirements of the United States Safety Appliance Act regulating structures of this nature in the 50 interest of the life and safety of railway employees. The sectional area of the ordinary sheet employed in structures of this nature is so small the pull on the rivet head would easily tear out or rupture the sheet 55 and permit the rivet head to pull through.

My invention consists in forming in the sheet A at the points of attachment of the ladder rounds thereto, the outwardly depressed saucer like indent B, provided at 60 its center with the rivet hole C. Snugly fitted into this indent is the circular metal disk or plate D provided with a rivet hole at its center in registration with the rivet hole in the sheet. As this disk can be made 65 of considerable thickness, it, together with the sheet, produces a sectional area of considerable proportions, affording sufficient surface contact to the rivet to insure a solid substantial joint or connection and absolutely prevent the tearing of the thin sheet. Ordinarily a heavy bar of iron would be riveted to the car side on which to fasten the ladder rounds. By the use of my improved means of reinforcing the thin sheet, 75 the use of this more expensive and unsightly bar is avoided.

What I claim is—

In combination, a thin sheet of metal provided with a centrally perforated indent or 80 recess, and a reinforcing element, centrally perforated in registration with the perforation in said sheet, filling said indent or recess.

Signed by me at Davenport, Iowa, this 35 2nd day of February 1914.

CLAUS J. WERNER CLASEN.
